(57) **CLAIM**

The ornamental design for a dual textured cosmetic pad, as shown and described.

DESCRIPTION

FIG. 1 is a bottom perspective view showing our new pad design;

FIG. 2 is a bottom plan view;

FIG. 3 is a top plan view;

FIG. 4 is a front elevational view;

FIG. 5 is a rear elevational view;

FIG. 6 is a left side elevational view; and,

FIG. 7 is a right side elevational view.

The portions of the dual textured cosmetic pad shown in broken lines are for illustrative purposes and form no part of the claimed design.

The stipple shading shown in FIGS. 1 and 2 represents the protruding fibers that are shown in FIGS. 4 through 7.
